HEDGE TRIMMER

Michael Kaminsky, New Britain, Conn.

Application February 6, 1939, Serial No. 254,914

12 Claims. (Cl. 30—213)

This invention relates to improvements in hand tools, and more particularly to hand-operated cutting tools, such as a hedge trimmer.

The form of the invention herein shown by way of example is a double-acting cutting tool, wherein a pair of cutter bars having overlapping toothed cutting blades are adapted to be reciprocated relatively to each other to shear the branches of hedges or the like.

It is among the primary objects of the present invention to provide a hand-operated cutting tool having releasable spring means operable during the cutting operation to impart a swift powerful movement between the blades, the speed and power of such movement being in excess of that normally obtainable by direct manual operation.

Another object is to provide a hand-operated cutting tool having means operable by the manual movement of the cutter handles in one direction to store energy in a spring for swiftly and powerfully moving said cutter in the opposite direction upon completion of said manual movement.

A more specific object is to provide a hedge trimmer in which the cutting blades are manually moved on the first stroke in one direction, and the reverse stroke taking place automatically with a snap action by power built up as a consequence of the manual movement.

A further object of this invention is to provide an improved hand tool of the above nature which will be relatively inexpensive to manufacture, simple in construction, compact, ornamental in appearance, and very efficient and durable in use.

With these and other objects in view, which will appear as the description proceeds, there have been illustrated in the accompanying drawings, two forms in which the invention may be conveniently embodied in practice.

In the drawings:

Fig. 1 is a perspective view of one form of hedge trimmer embodying the invention.

Fig. 2 is a top plan view of the same with the cover removed.

Fig. 3 is a front view of the same, looking in the direction of the arrow 3 of Fig. 2, the cover being sectioned to expose the interior parts of the tool.

Fig. 4 is a sectional view taken on the line 4—4 of Fig. 2.

Fig. 5 is a top plan view of a modified form of tool, the cover being removed for the sake of clearness.

Fig. 6 is a fragmentary front view of the same, 55

looking in the direction of the arrows 6—6 of Fig. 5.

Fig. 7 is a sectional view taken on the broken line 7—7 of Fig. 5.

Referring now to the drawings wherein like reference numerals designate like parts throughout the several views, the reference numerals 10 and 11 denote a pair of superposed bars having rows of cutter blades 12 and 13, each having double-edged V-shaped sharpened points formed thereon. The lower bar 10 is stationary and may be formed integral with a base plate 14, but is preferably secured thereto by rivets 15, as shown. The upper bar 11 is relatively movable and is connected with a slidable cutter bar 16, as by rivets 17.

The upper cutter bar 16 is slidably mounted upon the base plate 14 and is guided by a pair of spaced apart posts 18 and 19, which extend upwardly from the base plate 14 through a pair of elongated slots 20 and 21 formed in said bar 16. A flat washer 22 having a coiled spring 23 seated thereon surrounds each post 18 and 19, and a horizontal pin 24 in each case retains the washer 22 and spring 23 on the respective post 18, 19. The spring 23 located between the pin 24 and the washer 22 acts to maintain the blades 10 and 11 in cutting engagement while permitting free sliding action.

The cutter bar 16 is normally urged toward an abutment post 26 by means of a relatively strong coiled spring 27 to cause its end 25 to abut said post as shown in Fig. 2. The post 26 is preferably surrounded by a cushioning pad or cap 32 of leather or the like, secured to said post by a screw 33 to cushion the blows of the cutter bar end 25 under the urge of the spring 27. One end of the coiled spring 27 is connected to a post 28 on the bar 16, as by a screw 30, and its other end is secured to a post 29 on the plate 14 by a screw 31.

The base plate 14 extends rearwardly beyond the bar 16 and has a handle 34 rigidly secured thereto by rivets 35. A handle lever 36 is pivoted to the plate 14 upon a pin 37. The handle lever 36 has an arm 38 directed forwardly from the pin 37 toward the rear edge of the cutter bar 16, as clearly shown in Fig. 2. A post 40 is mounted on the plate 14 adjacent the pin 37 to limit the swinging movement of the handle 36 away from the handle 34. The outer end 43 of the arm 38 is provided with a dog 41 pivoted upon a pin 42. The dog 41 is provided with a tooth or catch lug 44, which is adapted to engage a tooth or shoulder 45 formed on the rear edge 39 of

the cutter bar, whereby when the two handles 34 and 36 are pressed together, the cutter bar 16 will be caused to slide along the plate 14 building up tension in the strong spring 27.

The lug 44 on the dog 41 is adapted to be released from the shoulder 45 after the opposing cutting edges of the teeth 12 and 13 have been manually moved by the handle 36 past each other in one direction by means now to be described so that the spring 27 will automatically move the teeth 12 and 13 in the other direction with a swift powerful snap action. The means for releasing the lug 44 from the shoulder 45 includes an extension member 46 formed on the dog 41 and a camming pin 47 secured on the base plate 14. The extension member 46 is provided with a camming edge 48, which is adapted to engage the pin 47 to rock the dog 41 upon its pivot pin 42 to disengage the lug 44 from the shoulder 45. The dog 41 is normally urged into position to cause the lug 44 to engage the shoulder 45 on the cutter bar 16 by a spring 49 acting upon a plunger 50, both slidably held in a bore 51 provided in the handle extension 38.

The spring-pressed plunger 50 engages the dog 41 at one side of the pivot pin 42 and urges the rear end 52 of said dog 41 against a stop shoulder 53 provided on the arm 38. A sheet metal cover 54 is provided to overlie the base plate 14 and the parts mounted thereon. The cover 54 is secured to the plate 14 by screws 55.

The first form of hedge trimmer shown in Figs. 1 to 4 inclusive has the handles 34 and 36 extending rearwardly away from the cutting teeth 12 and 13 and is intended for use to trim hedges or the like, disposed directly in front of the user. To enable the user to trim hedges located at the left of the direction the user is facing, the modified form of tool shown in Figs. 5 to 7 is provided. In this modified form the handles 56 and 57 extend in a direction substantially parallel to the toothed cutting blades 58 and 59.

The handle 56 is preferably formed integral with a base plate 60. The lower blades 58 may be formed integral with the plate 60, but preferably are secured thereto by rivets 61. The upper cutting blade 59 is also secured by rivets 62 to a cutter bar 63, which is adapted to reciprocate upon the plate 60. The cutter bar 63 is guided in its movement on the plate 60 by cooperating posts 64 and elongated slots 65, being secured in place by washers 66, coiled springs 67 and pins 68, as in the first form shown in Figs. 1 to 4. A strong coiled spring 69 is connected at each end to posts 70 and 71 mounted on the cutter bar 63 and the base plate 60, respectively. The spring 69 is tensioned to constantly urge the right end 72 of the bar 63 (see Fig. 5) toward the post 71.

The cutter bar 63 is adapted to be manually moved away from the post 71 by means of the handle lever 57, which is pivoted to the base plate 60 by a pin 75 and has an arm 76 extending therefrom toward the bar 63. A dog 77 is pivoted on the end of the arm 76 by a pin 78. A stop pin 79 is mounted on the base plate 60 at the right of the dog 77 to be engaged thereby to limit the movement of the handle lever 57 away from the fixed handle 56.

The dog 77 has a lug 80 formed thereon in position to engage a shoulder 81 provided in the rear edge 82 of the cutter bar 63 to cause said bar 63 to slide along the plate 60 away from the post 71 when the handles 56 and 57 are pressed toward each other. The dog 77 is limited in its pivotal movement on the pin 78 in one direc-

tion by a lug 83 on the arm 76 which cooperates with a shoulder 84 provided on the dog 77. A coiled spring 85 having its ends connected respectively to the dog 77 and the handle 57 is tensioned to urge the lug 83 on the arm 76 and the shoulder 84 on the dog 77 toward each other.

Provision is also made to release the lug 80 from the shoulder 81 at the end of the manual movement of the handles when pushed together, whereby the spring 69 will automatically move the teeth 73 and 74 past each other in the opposite direction with a rapid powerful snap action to shear an article between the cutting edges thereof. The means for so releasing the lug 80 from the shoulder 81 includes an extension finger 86 which extends outwardly from the dog 77 away from the lug 80. The extension finger 86 has a curved cam surface 87 formed thereon which is adapted to engage a camming post 88 mounted on the base plate 60 in the path of the curved surface 87 to swing the dog 77 upon its pivot pin 78, thus raising the lug 80 out of engagement with the shoulder 81 and suddenly releasing the spring-pressed cutter bar 63. A sheet metal cover 89 is provided as before to protect the operating parts mounted on the base plate 60 and is secured in place by screws 90.

Operation

When it is desired to trim the branches, etc., of hedges or the like, the user will grasp the handles 34 and 36, or 56 and 57, as the case may be, and manually push them toward each other. This action slides the cutter bar 16 or 63 along the base plate 14 or 60 to move the respective cutting teeth past each other in one direction for the first cutting stroke. At the end of the manual cutting stroke, the dog 41 or 77 will be released, causing the strong spring 27 or 69 to automatically retract the bar 16 or 63 along the base plate 14 or 60 to move the cutting teeth past each other in the other direction.

While there have been disclosed in this specification two forms in which the invention may be embodied, it is to be understood that these forms are shown for the purpose of illustration only, and that the invention is not to be limited to the specific disclosures, but may be embodied and modified in various other forms without departing from its spirit. In short, the invention includes all the modifications and embodiments coming within the scope of the following claims.

Having thus fully described the invention, what is claimed as new and for which it is desired to secure Letters Patent, is:

1. In a hedge trimmer, a fixed cutting member, a movable cutter member, a handle for operating the latter, spring means connected to both cutter members and energized by the movement of said movable cutter member in one direction, a catch movably mounted on said handle to initially hold said movable cutter member while it is being energized and means to suddenly disengage said catch from said movable cutter member to permit said spring to automatically return said movable cutter member to its original position when said movable cutter member has been moved to the end of its travel in the other direction.

2. In a hedge trimmer, a fixed cutting member, a movable cutter member, a handle for operating the latter, spring means connected to both cutter members and energized by the movement of said movable cutter member in one direction, a catch movably mounted on said handle

and connected with said movable cutter member while it is being energized and cam-operated means to suddenly disengage said catch from said movable cutter member to permit said spring to automatically return said movable cutter member to its original position when said movable cutter member has been moved to the end of its travel in the other direction.

3. In a hedge trimmer, a base plate having a handle fixed thereto, a handle lever pivoted to said base plate, a fixed cutter bar mounted on one edge of said base plate, a movable cutter bar initially operatively connected to said handle lever, spring means connected to said base plate and to said movable cutter bar for opposing the movement of said cutter bar in one direction, and means pivoted to said handle lever to suddenly disconnect said handle lever from said movable cutter bar when said lever has been swung a predetermined amount to cause said spring to automatically return said movable cutter bar to its original position with a snap action.

4. In a hedge trimmer, a base plate having a handle fixed thereto, a handle lever pivoted to said base plate and having a catch, a fixed cutter bar mounted on one edge of said base plate, a movable cutter bar operably connected to said handle lever by said catch, spring means connected to said base plate and to said movable cutter bar for opposing the movement of said cutter bar in one direction, means movably mounted on said handle lever to suddenly release said catch and disconnect said handle lever from said movable cutter bar when said lever has been swung a predetermined amount to cause said spring to automatically return said movable cutter bar to its original position with a snap action, said spring means being placed under tension by the swinging of said handle lever in one direction.

5. In a hedge trimmer, a base plate carrying a fixed cutter bar and a fixed handle, a handle operated movable cutter bar slidable with respect to said fixed cutter bar, a releasable spring for opposing the sliding movement of said movable cutter bar in one direction and being energized by said sliding movement, and cam means movably mounted on said handle responsive to a predetermined sliding movement of said handle to suddenly release said movable cutter bar from its operating handle to permit said energized spring to impart a snap-action to said movable cutter bar to return it to its original position.

6. In a hedge trimmer, a base plate having a cutter bar fixed thereto along one edge thereof, a movable cutter bar slidably mounted with respect to said fixed cutter bar, a spring connecting said base plate and said movable cutter bar to resist the movement of said movable cutter bar in one direction, a handle lever having a detachable connection with said movable cutter bar to move it in said direction and energize said spring, and means movably mounted on said handle lever responsive to a predetermined manual swinging of said handle lever to disconnect said lever from said movable cutter bar to permit said spring to automatically return the latter to its original position with a snap-action.

7. In a hedge trimmer, a base plate having a cutter bar fixed thereto along one edge thereof, a movable cutter bar slidably mounted with respect to said fixed cutter bar, a spring connecting said base plate and said movable cutter bar to resist the movement of said movable cutter bar in one direction, a handle lever having a detachable connection with said movable cutter bar to

move it in said direction and energize said spring, and cam means movably mounted on said handle lever responsive to a predetermined manual swinging of said handle lever to disconnect said lever from said movable cutter bar to permit said spring to automatically return the latter to its original position with a snap-action.

8. In a hedge trimmer, a base plate having a cutter bar fixed thereto along one edge thereof, a movable cutter bar slidably mounted with respect to said fixed cutter bar, a spring connecting said base plate and said movable cutter bar to resist the movement of said movable cutter bar in one direction, a handle lever having a detachable connection with said movable cutter bar to move it in said direction and energize said spring, and cam and latch means movably mounted on said handle lever responsive to a predetermined manual swinging of said handle lever to disconnect said lever from said movable cutter bar to permit said spring to automatically return the latter to its original position with a snap action.

9. In a hedge trimmer, a base plate having a plurality of double-edged teeth along one edge thereof, a cutter bar having a plurality of double-edged teeth slidably mounted on said base plate, the teeth on said plate and bar overlapping to cooperate with each other, a first handle secured to said base plate, a second handle pivoted to said base plate, releasable means pivoted to said first handle to connect said second handle to said cutter bar whereby said cutter bar will be moved by the manual pressing of said second handle toward said first handle, cam-operated catch means connected to said second handle to automatically release said second handle from said bar after a predetermined movement thereof, and spring means to suddenly retract said cutter bar to its original position when so released.

10. In a hedge trimmer, a base plate having a plurality of double-edged teeth along an edge thereof, a cutter bar having a plurality of double-edged teeth slidably mounted on said base plate, the teeth on said base plate and cutter bar overlapping to cooperate with each other, a first handle secured to said base plate, a handle lever pivoted to said base plate, a catch pivoted to said handle lever and engaging said cutter bar to releasably connect it to said lever, means to swing said catch to release said cutter bar from said handle lever, and a strong spring connecting said cutter bar and said base plate to suddenly retract said cutter bar after the latter is released from said second handle.

11. In a hedge trimmer, a base plate having a plurality of double-edged teeth along an edge thereof, a cutter bar having a plurality of double-edged teeth slidably mounted on said base plate, the teeth on said base plate and cutter bar overlapping to cooperate with each other, a first handle secured to said base plate, a handle lever pivoted to said base plate, a catch pivoted to said handle lever and engaging said cutter bar to releasably connect it to said lever, cam-actuated means to swing said catch to release said cutter bar from said handle lever after a certain movement of said handle lever, and a strong spring connecting said cutter bar and said base plate to suddenly retract said cutter bar after the latter is released from said second handle.

12. In a hedge trimmer, a base plate having a plurality of double-edged teeth along an edge thereof, a cutter bar having a plurality of double-edged teeth slidably mounted on said base plate, the teeth on said base plate and cutter bar over-

lapping to cooperate with each other, a first handle secured to said plate, a handle lever pivoted to said plate, a catch pivotally connected to said handle lever and engaging said cutter bar to releasably hold the same, said catch having a finger extending therefrom with a curved camming edge formed thereon, a pin on said base plate disposed in the path of said curved cam-

ming edge to automatically swing said catch out of engagement with said cutter bar, and a spring connecting said cutter bar with said base plate to be tensioned when said cutter bar is moved by said second handle, said spring acting to suddenly retract said cutter bar when it is released from said second handle.

MICHAEL KAMINSKY.
